UNITED STATES PATENT OFFICE.

ISADORE W. RENIER, OF EAST ST. LOUIS, ILLINOIS.

SUSPENSORY.

1,281,659.

Specification of Letters Patent.

Patented Oct. 15, 1918.

Application filed August 17, 1917. Serial No. 186,762.

To all whom it may concern:

Be it known that I, ISADORE W. RENIER, a citizen of the United States, residing at East St. Louis, in the county of St. Clair 5 and State of Illinois, have invented certain new and useful Improvements in Suspensories, of which the following is a specification.

This invention relates to certain new and 10 useful improvements in suspensories.

The primary object of the invention is to provide a device of this character which includes a supporting belt and a bag or sack adapted to be properly suspended from 15 the belt by means of adjustable straps; the bag being removable for cleaning or other purposes.

Another object of the invention is to provide a suspensory which can be readily attached in position and adjusted to properly support the parts affected, and one which will not irritate or annoy the wearer while in use.

The above and other objects of the invention will be in part described and in part 25 understood from the following description, of the present preferred embodiment, the same being illustrated in the accompanying drawings, in which,

30 Figure 1, is a perspective view of my invention.

Fig. 2, is a view of a detail and,

Fig. 3 is a side view of the bag or pouch.

In the drawings the numeral 1 indicates 35 a belt adapted to be secured around the waist of the wearer and provided at one end with a buckle 2, adapted to receive the opposite end of the belt. Secured to the rear part of this belt and depending therefrom are a pair of spaced supporting loops 3 which are to be employed in the manner hereafter set forth.

A bag or pouch is indicated at 4 and may be made in any convenient shape and of 45 any desired depth. Secured to opposite sides of the bag at one end thereof are a pair of straps 5. These straps 5 have their free ends doubled back upon themselves and sewed or otherwise secured to provide the 50 loops 6 which are adapted to be passed through the supporting loops 3 as shown.

A second pair of straps indicated at 7 are secured in like manner to the opposite ends of the bag and the free ends of these straps are adapted to be tied or otherwise de- 55 tachably secured to the looped ends 6 of the straps 5.

In the practical use of the suspensory the belt is adapted to be buckled around the waist of the wearer and the straps 5 and 7 60 when engaged with the loops 3 and secured together as described form a supporting sling which is adjustable to hold the bag 4 properly engaged with the parts affected.

Having thus fully described the preferred 65 form of my invention I wish it to be understood that I may resort to such minor changes in the construction and arrangement thereof as may be desired, providing of course that the changes contemplated come 70 within the scope of the appended claims.

What I claim is:—

1. A suspensory including a waist belt, supporting loops depending therefrom, a pouch, straps secured to one end of said 75 pouch and having their free ends doubled back upon themselves to provide loops adapted to be passed through said supporting loops and straps secured to the opposite end of the pouch and adapted to be fastened 80 to the looped ends of said first mentioned straps.

2. A device as described including a belt, straps depending therefrom, loops formed on the lower end of said straps, a pouch, a 85 pair of straps secured to opposite sides of said pouch adjacent one end thereof, said straps having their free ends extended through said loops and then doubled upon themselves to provide looped extremities, a 90 second pair of straps secured to opposite sides of said pouch adjacent its opposite end, said second straps having their free ends releasably tied to the looped ends of said first straps. 95

In testimony whereof I affix my signature in presence of two witnesses.

ISADORE W. RENIER.

Witnesses:

GEORGE M. LORNIS,
E. E. CLARK.
